UNITED STATES PATENT OFFICE

CLARENCE A. ANDERSON, OF CHICAGO, ILLINOIS, ASSIGNOR, BY MESNE ASSIGNMENTS, TO AMERICAN ELECTRIC COMPANY, INC., OF CHICAGO, ILLINOIS, A CORPORATION OF DELAWARE

TELEPHONE SYSTEM

Application filed July 20, 1927. Serial No. 207,161.

The present invention relates to telephone systems in general, but more particularly to telephone systems employing call indicators for indicating to an operator the destination of calls.

The present invention discloses novel sending means and novel receiving means for sending and receiving impulses corresponding to desired telephone numbers and for displaying these numbers before an operator, and has been applied to a telephone system wherein one or more trunk lines connect two telephone exchanges.

An object of the invention is the production of new and improved circuit arrangements whereby codes of impulses of different strength and polarities may be transmitted upon the depression of a digit key corresponding to a digit desired to be sent over a telephone line.

Another object of the invention is the production of new and improved relay arrangements in connection with the keys at the transmitting end of the circuit whereby a plurality of impulses may be sent out upon a single operation of a key, and whereby a sufficient space is provided between successive impulses to permit a switching operation to be accomplished at the receiving end of the circuit.

Another object of the invention is the production of new and improved arrangements at the receiving end of a telephone line to enable a reduction to be made in the number of spring contacts on the register relays in the receiver by arranging the receiving lamp banks in interconnected squares and by applying one potential to a vertical conductor of an interconnected square and another potential to a horizontal conductor to light the particular lamp common to both conductors.

Another object of the invention has to do with a reduction in the number of receiving relays required by suitably arranging a single relay to carry the spring contacts ordinarily carried by two relays and to cause the relay to differentiate between which of the two functions it is to perform by arranging it to operate through one step or through two steps as the occasion demands.

Another object of the invention is the production of a new and improved arrangement for operating the transfer relays used to transfer the receiving conductors from one set of receiving circuits to another as the code impulses are received.

There are other objects and features of the invention having to do more or less with the circuit details involved in carrying out the foregoing. The various objects and features of the invention can be understood best from a further perusal of the specification in connection with the accompanying drawings.

Referring now to the accompanying drawings comprising Figs. 1-3, Figs. 1 and 2 are circuit diagrams showing a sufficient amount of apparatus involved in a telephone system embodying the features of the invention to enable the invention to be understood, and Fig. 3 is a table showing the code according to which the impulses are transmitted and indicating the relays which respond to the various transmitted impulses.

Fig. 1 shows the outgoing end of a trunk line between two exchanges, together with the sending keys and the associated equipment.

Fig. 2 shows the incoming end of the trunk line in the second exchange including the various receiving relays and lamp sets.

Referring particularly to Fig. 3, which indicates the response of the receiving relays A1-C1, A2-C2, and A3-C3, Fig. 2, it will be noted that the digit 1, for example, is represented by a positive impulse and a negative impulse. Similarly, the digit 2 is represented by positive impulse and a negative impulse, but, as indicated by the fact that the positive sign of the digit 2 is made heavier than the positive sign of the digit 1, the positive impulse of the digit 1 is light, while the positive impulse of the digit 2 is heavy.

Similarly, a positive impulse and a negative impulse represent the digit 3, but in this case both impulses are heavy. The distinction between heavy impulses and light impulses is made according to whether a resistance, such as the resistances 21 and 22, Fig. 1, is included in the impulsing circuit at the

time the impulse is sent. A positive impulse, it may be pointed out, is one sent from the positive battery 24, while a negative impulse is one sent from the negative battery 23.

- 5 Still referring to Fig. 3, it will be noted that the relay A of the connected set is operated in response to the positive impulse of the digit 1, but it will be noted that no relay is operated in response to the negative impulse. The reason for this will appear subsequently. It will be noted further that relays A and C' respond in the connected set when the heavy positive impulse of the digit 2 is transmitted. It may be pointed out that the reference character C' is used to indicate that relay C of the connected set operates through its first step. The same response of the relays A and C' occurs when the heavy positive impulse of the digit 3 is transmitted, and relay C2 responds to the heavy negative impulse of the digit 3. The reference character C2 is meant to indicate that relay C of the connected set operates through its second step.
- 25 The invention having been discussed in general a detailed description will now be given. For this purpose it will be assumed that the operator in the first exchange receives a call for a connection to be extended to a line terminating in the second exchange. In order to extend the connection, the operator in the first exchange inserts the plug of a cord circuit (not shown) into the jack J1, Fig. 1, of the trunk line comprising conductors 25 and 26.
- 30 After having thus extended the connection, the operator transmits the desired number by pressing the proper ones of the keys K1—K10, which represent the digits 1—0, respectively. For the sake of illustration, it will be assumed that the number desired is 904.

When the operator depresses the key K9, conductor 25 is grounded at the inner right-hand contacts of the key, and a heavy negative impulse is placed on conductor 26 at the inner left-hand contacts of the key through the contacts of relay 11. At the outer right-hand contacts of the key K9, a circuit is closed for relay 19. Relays 19, as well as relay 20, is slightly slow to operate due to a stiff spring adjustment and due to a copper collar on the armature end of the core.

- 55 After a light interval of time has elapsed (sufficient to allow a full impulse to be transmitted), relay 19 operates and terminates the heavy negative impulse by disconnecting conductor 26 from the heavy negative impulse conductor extending up from the battery 23.
- 60 Relay 19 also closes a circuit for the auxiliary relay 20. After an interval sufficiently long to permit switching operations hereinafter described to take place, the slightly slow-to-operate relay 8 operates and places a heavy positive impulse on conductor 26 through the

outer left-hand contacts of the depressed key K9.

After having held the key K9 depressed for a sufficient interval, the operator releases the key, thereby terminating the heavy positive impulse and opening the circuit of relays 19 and 20. These relays fall back quickly due to their stiff spring adjustment.

When the operator depresses the key K10 to transmit the digit 0, two light negative impulses are transmitted through the battery 23 and the resistance 21, relays 20 and 19 operating as above described.

When the operator depresses the key K4 to transmit the digit 4, two light positive impulses are transmitted from the battery 24 through the resistance 22 by the action of the relays 20 and 19.

After the operator has finished transmitting the code impulses, the keys are all in the position shown and the trunk line comprising conductors 25 and 26 is clear for voice-current transmission.

Referring now to Fig. 2, when the heavy negative impulse of the digit 9 passes through the receiving relays 51—53, the marginal relay 53 and relay 52 are operated, but the positively polarized relay 51 is not operated by the negative impulse. When the marginal relay 53 is operated, a circuit is closed for relay C1 through the lower armature of relay 55 and the resistance associated with relay C1. When operated through the associated resistance, relay C1 operates through its first step only, operating its left hand armatures. At its inner left hand armature, relay C1 closes a locking circuit for itself through the associated resistance, and at its outer left hand armature it removes ground from the vertical conductor common to the lamps 1, 4, and 7 and places ground on the conductor common to the lamps 2, 5 and 8 through the right hand armature of the relay, which armature shifts only when the relay is operated through its second step.

When the relay 52 responds to the impulse, it opens the circuit of the upper winding of the differential relay 55 and connects the upper winding of relay 55 in multiple with the winding of the auxiliary relay 54. Relay 55 now energizes through its lower winding from ground on the locking conductor through the release button RB. Relay 55 is adjusted so that its inner upper armature is very sensitive and operates first. The remaining armatures of the relay are rather stiffly adjusted with the result that the relay hesitates for an appreciable length of time before operating further after the lightly adjusted inner upper armature has operated. When this armature operates, it disconnects the operating conductor 75 from the upper winding of relay 55 and connects it to ground through the adjacent upper armature, which as is noted on the drawings breaks contact

last, that is, after all other armatures of the relay have operated. During the interval required for the relay to complete its operation after the inner upper armature has shifted, as above described, relay 54 is operated from ground on conductor 75 through the operated contacts of relay 52. When relay 54 operates it locks itself operated by placing a multiple ground connection on conductor 75 so that it will remain operated and maintain conductor 75 grounded as long as the impulse endures and maintains relay 52 operated.

When relay 55 has operated fully, it breaks the ground connection (at its break-last contacts) from the extension of operating conductor 75, which would allow the current to cease flowing in the upper winding of the differential relay 56 if it were not for the multiple ground connection on conductor 75 at the auxiliary relay 54. Relay 52 falls back at the end of the impulse, as does the marginal relay 53 and opens the circuit of relay 54, at the same time replacing the normal ground connection on conductor 75. Relay 54 now falls back, leaving conductor 75 grounded only at the normal contacts of relay 52. This ground potential on conductor 75 maintains the differential relay 56 non-operated.

As a further result of the operation of relay 55, it transfers the relay-operating circuit controlled by the marginal relay 53 from the circuit of relay C1, through the associated resistance, through the lower armature of relay 56 to the winding of relay C1 direct. Relay 55 also makes a similar transfer of the relay operating conductors controlled by the polarized relay 51 from relay A1 to relay B1 through the upper contacts of relay 56. At its upper armature, relay 55 closes a circuit for the 0 lamp through contacts of the non-operated relays A1 and B1. As a result the 0 lamp is lighted unless one or the other of the relays A1 and B1 is operated, as will now take place.

When the heavy positive impulse of the digit 9 is received by the receiving relays, all three relays operate. The marginal relay 53 closes a circuit through the lower armature, operated, of relay 55 and through the lower armature, normal, of relay 56 for the relay C1 independent of the associated resistance. As a result, relay C1 operates through its second step, and remains operated through its second step even after this circuit is opened, owing to the fact that the current flow through the associated resistance and through the locking contacts of the relay is sufficient to maintain the relay completely operated after it has once been operated fully. The right-hand armature of relay C1 transfers the ground potential from the vertical conductor common to the lamps 2, 5 and 8 to

the vertical conductor common to the lamps 3, 6 and 9.

When the positively polarized relay 51 operates, it closes a circuit thru the corresponding armature, operated, of relay 55 and through the upper armature, normal, of relay 56 for the left-hand winding of relay B1. Relay B1 operates and locks itself to the associated locking conductor and at its left-hand armature it opens the circuit of the 0 lamp, and places battery through the inner armature, normal, of relay 8 on the horizontal conductor common to the lamps 7, 8 and 9. After this, the full potential is across the terminals of the lamp 9, and this lamp is lighted. An examination will show that there is a slight current flowing through each of the other lamps due to the way in which the common conductors are connected to the lamps, but the potential across no other lamp is equal to half the full potential. The result is that the standard switchboard lamps assumed to be used (they are usually of the carbon filament type) fail to light, with the exception of the lamp 9.

When the transfer control relay 52 responds, it removes ground from conductor 75 and connects this conductor to the auxiliary relay 54. As a result, relay 56 operates in the same manner as described in connection with relay 55 and transfers conductor 75 to relay 57. The auxiliary relay 54, as before, maintains conductor 75 grounded as long as relay 52 remains operated, so as to prevent the next relay in the transfer chain from operating prematurely. The operating circuits controlled by the receiving relays are now transferred through contacts of relay 57 to the tens register.

When the first light negative impulse of the digit 0 is received, receiving relay 52 alone responds, relay 53 being marginal and relay 51 being positively polarized.

Upon responding, relay 52 aided by the auxiliary relay 54, brings about the operation of relay 57, whereupon the operating circuits are transferred to relay 58. A circuit is closed for the 0 lamp of the tens set at the upper contacts of relay 57, whereupon the 0 lamp becomes lighted.

When the second light negative impulse of the digit 0 is received, receiving relay 52 responds alone and brings about the operation of the transfer relay 58, whereupon the operating circuits are transferred to relay 59. As none of the relays A2—C2 are operated the lamp 0 is lighted alone and the lamps 1—9 are not lighted.

When the first light positive impulse of the digit 4 is received, relays 52 and 51 both respond, and relay 51 closes a circuit through the associated contacts of relays 54—59 for the left hand winding of relay A3. Relay A3 operates and closes a locking circuit for itself at its right hand armature, and at its outer

left-hand armature it removes battery from the lower terminal of the 0 lamp and places battery on the horizontal conductor common to the lamps 1, 2, and 3. Relay 59 responds in the hereinbefore described manner to the operation of the transfer control relay 52.

When the second light positive impulse of the digit 4 is received, relays 51 and 52 respond as before, and relay 51 closes at this time a circuit through the associated contacts of relays 54-60 for the left-hand winding of relay B3. Relay B3 operates and locks itself, at the same time transferring the battery potential from the horizontal conductor common to lamps 1, 2 and 3 to the conductor common to the lamps 4, 5 and 6. Relay 60 responds to the operation of relay 52 and disconnects the operating conductors from the windings of the relays B3 and C3. Since battery is now placed through the contacts of the operated relays A3 and B3 on the horizontal conductor common to lamps 4, 5, and 6, and, since relay C3, being non-operated, permits the ground potential to remain on the conductor common to lamps 1, 4, and 7, the lamp 4 alone is lighted.

As a result of the foregoing operations, the ninth lamp in the hundreds set, the tenth lamp in the tens set, and the fourth lamp in the units set are lighted to display to the operator the desired number 904. The operator in this exchange may now insert the plug of a cord circuit into the jack J2 and complete the desired connection.

After the operator has noted the desired number, she releases the operated equipment by momentarily operating the release button RB, whereupon the locked up relays fall back, extinguishing the lighted lamps and restoring the circuits to normal.

When the conversation is terminated, as may be discovered by the operator in the originating exchange by listening in in the usual manner, the originating operator may transmit a disconnect number over the exchange trunk line comprising conductors 25 and 26. This disconnect number may be some arbitrary number such as, for example, 111, or perhaps 000.

Upon perceiving the disconnect number transmitted over the interexchange trunk line by the operator in the first exchange, the operator in the second exchange may release the indicating equipment and take down the connection. The connection in the first exchange is taken down by the operator therein.

From the foregoing description, it will be obvious how the other digits are transmitted when desired.

It will be apparent that relay C1 may be replaced, if desired, by two relays, each relay carrying locking contacts, one relay carrying the first-step switching contacts and the other relay carrying the second-step switching contacts. The first relay would, of course, be

operated over the conductor connected to the back contact of the lower armature of relay 55, and the second relay would, of course, be connected to the conductor extending from the back contact of the lower armature of relay 56. The same arrangement may be applied to the relays C2 and C3.

What is claimed is:—

1. In an impulse receiving device, a chain of differential transfer relays, a transfer-control relay, an auxiliary relay, means responsive to an operation of the transfer-control relay for bringing about the operation of the first differential relay, a circuit for said auxiliary relay controlled jointly by said transfer-control relay and any connected one of the differential relays, and circuit arrangements controlled by the auxiliary relay for preventing the operation of the next differential relay until the transfer-control relay has released and has reoperated. 75

2. In a relay register, a plurality of indicating devices, vertical and horizontal conductors interconnecting said devices, each conductor being common to a separate plurality of said devices, relay contacts for placing a given potential on any one of the vertical common conductors, and relay contacts for placing a different potential on any one of the horizontal conductors, whereby an effective current flow is produced through only one of said indicating devices. 80

3. In a relay register, a two step relay arranged to be operated through its first step or through its second step to register either of two different conditions, and a locking circuit for said relay effective to maintain the relay in either of its two operated steps. 100

4. In combination, an impulse transmitter arranged to transmit digit-indicating impulse combinations in accordance with a code containing impulses of two polarities, with two strengths of impulse for each polarity, and two impulses per digit, and an impulse receiver and indicator arranged to respond to the impulses transmitted by said impulse transmitter in accordance with said code to indicate the digits transmitted. 105

5. In an impulse transmitting and receiving system, an impulse transmitter arranged to transmit a plurality of impulses, any impulse to be of either positive or negative polarity and of either light or heavy strength, and an impulse receiver for receiving and indicating the received impulses, the indication being different depending upon whether a received impulse is of one polarity or the other, and also upon whether it is of heavy or light strength. 115

6. In an impulse transmitting and receiving system, means for transmitting impulses characterized both by their polarity and by their strength, and a receiving device for receiving the transmitted impulses comprising a polarized relay responsive to impulses of a 120 125 130

given polarity only, a non-polarized marginal relay responsive to heavy impulses only of either polarity, and a non-marginal, non-polarized relay responsive to all received impulses regardless of their strength or polarity.

7. In a telephone system, a trunk line over which telephone connections are to be set up, said trunk line extending from a manual switchboard in a first exchange to a manual switchboard in a second exchange, an impulse transmitter at the first switchboard permanently connected to said trunk line and arranged to be controlled by the operator thereat to transmit impulses in accordance with the digits in desired telephone numbers, and a visual indicating receiver at the second switchboard permanently connected to said line and arranged to be controlled thereover by the impulses sent out by said transmitter to indicate to the operator at the second switchboard to where the connections are to be set up, said transmitter being arranged so that the voice currents do not flow through it during conversation, and the receiving device being so designed that the flow of voice current through it during conversation is relatively small.

8. In a telephone system, two exchanges, a trunk line extending from a manual switchboard in the first exchange to a manual switchboard in the second exchange, a digit receiver and indicator at the manual switchboard in the second exchange permanently connected to said trunk line, and means under the control of the operator at the manual switchboard in the first exchange for operating the receiver and indicator over said trunk line to indicate the respective numbers of lines to which connections are to be set up over the trunk line from the first switchboard to the second switchboard.

9. In a telephone system, two exchanges, a trunk line extending from a manual switchboard in the first exchange to a manual switchboard in the second exchange, a digit receiver and indicator at the manual switchboard in the second exchange permanently connected to said trunk line, means under the control of the operator at the manual switchboard in the first exchange for operating the receiver and indicator over said trunk line to indicate the respective numbers of lines to which connections are to be set up over the trunk line from the first switchboard to the second switchboard, means under the control of the operator at the second switchboard for restoring the receiver and indicator, said means under the control of the operator in the first exchange being again effective for operating the receiver and indicator over said trunk line to indicate to the operator at the second switchboard when the established connection is to be taken down.

10. In combination, means for transmit-

ting and means for receiving the digits of a number in accordance with a code comprising four characters arranged in ten combinations, each combination including two and only two of said characters.

11. In a telephone system, a trunk line connecting two exchanges, a transmitter in one exchange arranged to transmit four kinds of impulses over said trunk line, a receiver in the other exchange arranged to receive the four kinds of impulses over said trunk line and to distinguish between them, said transmitter and receiver being arranged to transmit and receive the impulses in ten different combinations, each combination including two and only two of said impulses.

12. In a telephone system, a trunk line connecting two exchanges, a transmitter in one exchange arranged to transmit four kinds of impulses over said trunk line, a receiver in the other exchange arranged to receive the four kinds of impulses over said trunk line and to distinguish between them, said transmitter and receiver being arranged to transmit and receive the impulses in ten different combinations, each combination including the same number of impulses as any other combination.

In witness whereof, I hereunto subscribe my name this 15th day of July, A. D. 1927.

CLARENCE A. ANDERSON.
